UNITED STATES PATENT OFFICE.

OTTO S. SCHAIRER, OF EDGEWOOD PARK, PENNSYLVANIA, ASSIGNOR TO WESTINGHOUSE ELECTRIC AND MANUFACTURING COMPANY, A CORPORATION OF PENNSYLVANIA

ELECTRICAL REGULATOR.

1,147,687.

Specification of Letters Patent. Patented July 20, 1915.

Application filed October 5, 1911, Serial No. 652,996. Renewed April 14, 1915. Serial No. 21,451.

To all whom it may concern:

Be it known that I, OTTO S. SCHAIRER, a citizen of the United States, and a resident of Edgewood Park, in the county of Allegheny and State of Pennsylvania, have invented a new and useful Improvement in Electrical Regulators, of which the following is a specification.

My invention relates to electrical regulators, and it has for its object to provide a simple and effective voltage or current regulator of the kind in which the regulation is effected by adjustment of the field excitation of a dynamo-electric machine.

My invention is illustrated in the accompanying drawing, Figure 1 of which is a diagrammatic view of a system embodying the same, and Fig. 2 of which is a similar view of a system embodying a modification of the regulator.

As illustrated in Fig. 1, the system in connection with which the present invention is employed comprises a main generator, the armature 1 of which is connected to a suitable distributing circuit 2-3-4 and the field magnet winding 5 of which is supplied with exciting current from the armature 6 of an exciter. The field magnet winding 7 of the exciter is here shown as supplied from the exciter armature, though, if desired, it may be supplied from any other suitable source, and in series therewith, is a resistor 8 that is adapted to be shunted by a pair of coöperating stationary and movable contact terminals 9 and 10 of a relay. The relay is also provided with a second set of coöperating stationary and movable contact terminals 11 and 12, which are adapted to make and break a shunt circuit to a resistor 13 that is connected in series with the field magnet winding 14 of an auxiliary generator. The armature 15 of the auxiliary generator may be driven by any suitable source of power, but, as illustrated, is preferably driven by a motor 16 that receives energy from the circuit 2-3-4, the motor and the auxiliary generator constituting a motor-generator set.

The relay, of which the contact terminals 9 to 12, inclusive, constitute parts, is provided with an actuating electromagnet winding 18 that is supplied with current from

the auxiliary generator and the circuit of which is controlled by a pair of coöperating stationary and movable contact terminals 19 and 20, the stationary terminal 19 being preferably mounted upon the end of a spring 21 or being otherwise resiliently supported. The contact terminal 20 is carried by a lever 23 that is pivotally or otherwise suitably connected at different points to the cores 24 and 25, or other movable parts, of two electromagnetic actuating devices for the lever. The core 24 is somewhat more than supported by a spring 26, so that the member 20 is normally held in engagement with the member 19, and the core is provided with an actuating winding 27 that acts, when sufficiently energized, to draw the same downwardly in opposition to the spring 26, the said winding being supplied from the armature 15 of the auxiliary generator. The core 25 is, in Fig. 1, only partially counterbalanced by a spring 28, though any other suitable counterbalancing means may be employed instead of the spring, and an actuating winding 29 is provided to raise the core 25. The winding 29 is supplied with energy from the circuit 2-3-4, as, for instance, by being connected, through a transformer 30, to conductors 2 and 3. When thus connected, the winding is energized in proportion to the voltage of the distributing circuit and varies the distance of the member 20 from the member 19 accordingly, though the connections may be suitably arranged by anyone skilled in the art so that the position of the member 20 may be adjusted in accordance with variations of any other electrical condition of a circuit. The movements of the core 25 are preferably retarded by a dash pot 31, and a stop 33 is provided beneath the lever 23, adjacent to the point of connection thereto of the core 25, in order to limit the downward movement of the core 25.

As the cores 24 and 25 are pivotally or otherwise loosely connected to the lever 23 at different points, it is obvious that each of the windings 27 and 29 may actuate the movable contact terminal 20 independently of the other, and that the point of connection of each of the cores to the lever serves as a fulcrum or pivotal point for the lever.

The winding 29 varies the position of the contact terminal 20 and, thereby, its distance from the contact terminal 19, in response to variations of the voltage, current or other electrical condition of the circuits 2-3-4, depending upon the manner of its association therewith, while the winding 27 is energized to varying degrees by the fluctuations of the voltage of the armature 15 of 10 the auxiliary generator and thereby moves the contact terminal 20 into and out of engagement with the contact terminal 19, the periods of engagement and disengagement of the contact terminals 19 and 20 depending 15 upon the position of the contact terminal 20 as determined by the winding 29.

The manner in which the winding 27 causes the contact terminal 20 to move into and out of engagement with the member 19 20 will be best understood from a detailed consideration of the mode of operation of the apparatus. When the members 19 and 20 are out of engagement, as illustrated, the contact terminals 10 and 12 of the relay are 25 also out of engagement with the corresponding stationary terminals 9 and 11. The shunt circuits to the resistors 8 and 13 are accordingly interrupted and the excitations and voltages of the respective field magnet 30 windings 7 and 14 of the exciter and the auxiliary generator, are diminished. The diminished voltage of the exciter is followed by a diminished field excitation of the main generator and by a reduction of 35 its voltage, which, acting through the coil 29, tends to raise the contact terminal 20. At the same time, the diminished voltage of the auxiliary generator results in a diminished energization of the winding 27, and 40 the spring 26 accordingly draws the contact terminal 20 into engagement with the contact terminal 19. Upon engagement of the contact terminals 19 and 20, the relay magnet winding 18 is energized and the contact 45 terminals 10 and 12 are brought into engagement with the contact terminals 9 and 11, with the result that the resistors 8 and 13 are shunted. This is followed by increased field excitations and voltages, 50 respectively, of the exciter and the auxiliary generator, and the increase of the exciter voltage is in turn followed by an increase of the excitation and voltage of the main generator. This, acting through the coil 29, 55 causes the contact terminal 20 to be lowered slightly. At the same time, the increased voltage of the auxiliary generator causes an increased energization of the winding 27, which, acting in opposition to the spring 26, 60 draws the contact terminal 20 downwardly, out of engagement with the contact terminal 19.

The operation of the regulator continues 65 in this manner, the periods of engagement and disengagement of the contact terminals

19 and 20 depending entirely upon the electrical condition of the distributing circuit and being automatically adjusted to maintain the voltage of the said circuit substantially uniform or at a desired value. 70

In the system of Fig. 2, the regulator is employed for maintaining a substantially uniform load upon a generator 35 that supplies a distributing circuit, between the conductors 36 and 37 of which a storage battery 75 38 and the armature 39 of a booster are connected, the battery being caused to charge when the load upon the distributing circuit is light and to discharge when the said load is heavy. In order to cause the battery to 80 charge and discharge under the varying conditions of load, the electromotive force of the booster armature is reversible, and, to this end, it is provided with differential field magnet windings 40 and 41, the former of 85 which is connected to suitable points of the battery, and the latter of which is supplied from the armature 42 of an exciter having a shunt excited field magnet winding 43 in series with which is a resistor 44. The 90 terminals of the resistor 44 are connected to stationary and movable contact terminals 45 and 46, respectively, of a relay 47 having an actuating magnet winding 48 that receives its energy from the battery, and the circuit 95 of which is governed by the coöperating stationary and movable contact members 49 and 50 of the regulator.

The regulator is similar in construction and operation to that of Fig. 1, but its actuating winding 51, which corresponds to the winding 29 of Fig. 1, receives current proportional to that traversing the distributing circuit conductor 36 and an adjustable counterweight 52 is substituted for the spring 28 of Fig. 1. The actuating winding 56 of the regulator in this case is supplied with current from the battery, and its circuit is periodically established and interrupted by means of a second set of contact 105 members 57 and 58 of the relay 47, the said winding being thereby intermittently energized to effect vibration of the lever. 110

The operation of the regulator is similar to that of Fig. 1, but, instead of regulating the 115 voltage of the main generator, it regulates the direction and value of the voltage of the booster in accordance with fluctuations of the load upon the distributing circuit, so as to maintain the load upon the main generator 120 substantially uniform. This will be readily understood by first considering that the load upon the distributing circuit 36-37 is light, under which condition the periods of engagement and disengagement of the contact 125 terminals 49 and 50 and of the relay contact terminals 45 and 46 will be in such relation that the resultant booster field excitation will be in the proper direction and of such value that the voltage of the booster 130

- armature will oppose the voltage of the battery and cause the same to be charged. When the load upon the distributing circuit is heavy and of substantially its normal value, the regulator will operate to cause the booster voltage to be substantially zero, so that the battery will simply float upon the system. When the load is still heavier, the periods of engagement and disengagement of the various contact terminals of the regulator will be in such relation that the voltage of the booster armature will supplement that of the battery, and the battery will be caused to discharge and thus assist in carrying the load, thereby relieving the generator. In this manner, the load upon the generator is maintained substantially uniform, the battery being caused to carry the fluctuations.
- 20 It will be readily understood that the regulator may be adapted to maintain other conditions substantially uniform or at desired values than those set forth in connection with Figs. 1 and 2, and to regulate in accordance with variations of any other electrical condition of a circuit or system, without departing from the spirit of the invention. The regulator may also be employed
- in connection with direct current machines, as well as with alternators. 30
- I claim as my invention:
1. A regulator comprising coöperating contact members one of which is resiliently mounted, a lever carrying the other member, two electromagnets for actuating the lever, and resilient means partially supporting said lever, the lever being supported only by the electromagnets and resilient means. 35
  2. A regulator comprising coöperating contact members one of which is resiliently mounted, a lever carrying the other member, two electromagnets for actuating the lever having armatures attached to the lever, and resilient means supporting said lever at the points of attachment of the armatures thereto, the lever being supported only by the electromagnet armatures and the resilient means. 40
- 45 In testimony whereof, I have hereunto subscribed my name this 29th day of September, 1911.

OTTO S. SCHAIRER.
